UNITED STATES PATENT OFFICE.

AUGUSTIN NORMAND, OF LE HAVRE, FRANCE.

BOILER-FURNACE.

1,078,803.

Specification of Letters Patent. Patented Nov. 18, 1913.

Application filed November 11, 1909. Serial No. 527,429.

To all whom it may concern:

Be it known that I, AUGUSTIN NORMAND, citizen of the Republic of France, residing at Le Havre, Department of the Seine-Inferieure, have invented certain new and useful Improvements in Boiler-Furnaces; and I do hereby declare the following to be a full, clear, and exact description of the invention, such as will enable others skilled in the art to which it appertains to make and use the same.

This invention relates to boiler furnaces, and the object of the invention is to provide an improved furnace by means of which the boiler may be heated with either oil or coal or simultaneously with both oil and coal, as desired.

The novel features of the invention will appear from the following description and claim.

In the accompanying drawing, Figure 1 is a vertical longitudinal section of a boiler furnace embodying the invention, and Fig. 2 is a detail view showing the manner of actuating the shutters in Fig. 1.

Referring to the drawing, the furnace proper, denoted by the numeral 1, is illustrated as of the usual form employed for the heating of boilers by means of coal, and the boiler is shown as supported on the front furnace wall 8. Below the grate 2 there is arranged an ash pit 4, communicating with the atmosphere by means of doors 5, and the doors 10 to be hereinafter described, and the grate may be charged with fuel through the usual door 3.

Associated with the front wall of the furnace, preferably above the door 3, are a plurality of separate oil burners. Only one of these burners is shown in Fig. 1, but it will be understood that they extend across the front furnace wall in a suitably arranged series as indicated, for example, in Letters Patent No. 926,958, July 6, 1909, to M. A. Normand. Each burner may comprise a sprayer or atomizer 6 to which the oil is supplied, and from which it is sprayed into an air nipple 7 communicating with an opening in the furnace wall 8, and in which the mixture of air and oil is produced. In the drawing, the nipple 7 is illustrated as of sleeve-like form, open at both ends, but it is to be understood that this exact construc-

tion need not be adopted in all cases. In the example shown, however, when the oil is sprayed into the nipple it meets a body of air passing into the nipple through the open front end of the latter, and the burning mixture of air and oil passes directly into the furnace, as will be understood. In order to control the passage of air through each nipple 7, the latter has associated therewith a movable shutter 9, of suitable type, which may close the nipple entirely if desired. This is done when it is wished to cut off the supply of oil and to heat the boiler with coal. When the boiler is to be heated with both oil and coal, the shutters 9 are opened and the oil burner operates in the ordinary manner, the air being admitted to the nipple either at its front face or through lateral apertures. The burner is arranged in a box or casing 11 serving as a support and through which the air is admitted. This box is provided with doors 10 which may be either balanced or not. The box 11 communicates with the ash pit, the door 5 of which is controlled by the air itself or by appropriate operating devices. Heating may be effected by means of coal alone when the shutters 9 are closed.

The shutters 9 are preferably actuated by the mechanism disclosed in Fig. 2 in which the shutter 9 slides in a guide-way 15 and is provided with a slot 19. A suitable bell-crank lever is pivoted at 16 and one of its arms 18 carries a stud which engages in the slot 19. The second arm 17 of the said bell-crank lever can be actuated to produce a longitudinal movement of the shutter 9 in the guide-ways 15.

The invention is not limited to the constructions illustrated in the drawing; the form of the obturators may be varied and they may either be single or double with hinges or slideways and so forth. The air inlets to the ash pit may likewise be arranged in any convenient manner, either laterally or at the rear of the boiler and the operation may be automatic or otherwise.

The arrangements described are applicable to boiler furnaces either with a natural or forced draft. The invention is also applicable to all boiler furnaces in which the air is conducted either to the closed ash pit

for operating with coal or to the air box or to each burner for firing with combustible oil.

What I claim is:—

5. An oil burner adapted to be used in connection with furnaces, comprising an atomizer, a sleeve-like air supplying nipple co-operating with said atomizer adapted to communicate with the interior of a furnace, adjustable shutters at the point of communication, a casing inclosing the nipple and the
- 10.
- 15.

ejector end of the atomizer, adjustable means in said casing for admitting air to the nipple, and means for operating the said shutters.

15. In testimony whereof I affix my signature, in presence of two witnesses.

AUGUSTIN NORMAND.
